TRAVERSING SUPPORT FOR METAL WORK-
ING MACHINES

Henry E. Morton, Muskegon Heights, Mich.

Application April 13, 1931. Serial No. 529,580

7 Claims. (Cl. 90—38)

This invention relates to a metal planing and milling machine of the draw-cut traveling head type and more definitely to a novel mounting means adapted to be applied between the several 5 slidably movable parts.

One difficulty of machines of this type and class as hitherto constructed resides in the mounting of the reciprocating ram which carries the cutting or finishing tool. As is well understood by those skilled in this art, the tool, which operates upon the object being machined, must be held rigid in order to avoid chattering thereof with consequent poor work and, obviously, any lateral movement, however slight, of the tool, is 10 undesirable. As the length of the stroke of the ram increases, additional difficulty is had along this line as the strains increase in multiplied proportion with respect to the additional throw or movement of the tool and hence, in machines 15 of this extraordinary large size, it is very necessary that the several sliding members have exceedingly slight play between them in either direction.

I overcome the above difficulty by providing two 20 sets of ways or guiding surfaces between each set of sliding members, one set of ways taking care of movement between the sliding members which occurs in one plane and the other set of ways taking care of the movement of the members in 25 a plane at right angles to the aforesaid plane. In other words, there are two sets of guiding surfaces between each set of sliding members and these surfaces are at right angles to each other.

Another difficulty encountered in machines of 30 the herein described type lies in the fact that the weight relief springs, these springs being under adjustable compression and inserted between the horizontally sliding column and a rolling carriage which runs upon a track upon the bed plate 35 to thereby relieve the dead weight of the sliding column upon the bed plate, such operation and construction being set forth in my Patent No. 682,218, September 10, 1901, are prone to incline from the vertical whereby a tendency is had to 40 throw the weight of the column unequally upon its spaced ways or guiding surfaces.

I eliminate the difficulty just recited by providing two sets of springs, these springs being individually capable of adjustment thus permitting 45 a proper compressing of each one whereby the turning of the column about its base may be done away with.

Other objects and advantages will appear during the understanding of my invention.

In the drawings:

Figure 1 is a side view of a machine embodying my invention.

Figure 2 is a view taken at right angles to Figure 1, parts being broken away in order to expedite the showing.

Figure 3 is an enlarged view taken along the plane of line 3—3 of Figure 2.

Figure 4 is a view in cross section taken along the line 4—4 of Figure 3.

Figure 5 is a typical view in cross section illustrating the sliding connection between either of the sliding members and their respective supports.

Figure 6 is a side view of the adjusting wedge screw.

Figure 7 is a view in cross section taken through the weight relief mechanism as indicated by the line 7—7 on Figure 4.

Figure 8 is a diagrammatic view taken in plan particularly illustrating the ways and gib which prevent play of the tool about a vertical axis.

Figure 9 is a view similar to Figure 8 but illustrating the ways and gib which prevent any slight movement or play about a longitudinal axis through the machine.

Similar numerals refer to similar parts throughout the several views.

The machine, as shown in Figs. 1 and 2, consists of a bed plate or base 10 having a column 30 slidably mounted thereupon, this column supporting a vertically movable saddle or apron 50, the saddle in turn carrying the reciprocated shaper bar or ram 70 having a tool carrying head 71 with a tool 72 properly mounted therein.

The vertically movable saddle 50 carries a motor 51 which reciprocates the bar 70 through suitable mechanism. Another motor 52 is mounted upon the saddle 50 and rotates the splined shaft 53, this shaft being vertically mounted in the column 30 and serving to rotate the traveling nut 54, this nut 54 being threadedly engaged upon the horizontal screw 55 whereby the column and all of its appurtenances is slid backward and forward as desired, thus bringing the tool 72 into its aligned position. The motor 52 also serves to vertically adjust the saddle member by mechanism interposed between the spline shaft and the threaded screw 56, this interconnecting mechanism not being shown.

The bed plate or base 10 has upper surfaces 11, and outwardly extending ribs 12, these ribs being faced on their lower sides to provide a surface against which the gib 13 are placed. The column 30 has a bottom plate 31 with overhanging dovetail portions 32 which fit against 110

the underside of the gibs 13. Bolts 33 extend horizontally through the overhanging portions 32 and thread into the gibs 13 whereby the gibs may be wedged upwardly against the portions 12 on the base plate. See Figs. 3 and 5.

5 The guide means just recited prevents any vertical play between the column and the base plate upon which it horizontally slides and the gibs 13 can be adjusted so that pressure upwardly on the tool will not cause deflection of the 10 column from its vertical position.

The bed plate has a depressed groove 14 which receives a gib holder 15 bolted to the base of the column as at 16. The gib holder supports gibs 17, see Figs. 3 and 4, and similar gibs 17 are seated in a groove formed in the overhanging portion of the column base 31 at one side of the machine as clearly shown in Fig. 3. These gibs 17 guidingly engage against vertical portions of the bed plate or base and the gibs 17, see also 20 Fig. 5, have inclined portions 18 which are engaged by the wedge portions 19 of the wedge screws 20.

Bolts 9, see Fig. 4, extend through the overhanging portion 32 of the column base 31 and 25 serve to draw and maintain the gibs 17 tightly against the wedge portions 19 of the wedge screws 20. Each of the wedge screws 20 has a stem 21 which receives a threaded cylindrical 30 member or sleeve 22 revolvably thereon. The threaded sleeve 22 is hexagonally shaped as indicated at 23 in order that it may be rotated as desired and a ring 24 serves to maintain the sleeve member 22 upon the stem 21. See Fig. 6. A nut 35 25 serves to lock the wedge screw in its adjusted position.

As shown in Fig. 5 the column base 31 has a 40 series of holes 26 extending upwardly from underneath one of its overhanging portions and these holes 26 are threaded to receive the members 22 at their lower portions and the upper tapered portion of the wedge screw extends upwardly back of the longitudinally located gib 17 whereby the same may be adjusted tightly 45 against the outer face of the rib 12 on the bed plate. Another set of openings 27 extend downwardly through the member 31 and receive similar wedge screws 20 which abut against the other gib 17 and thus render it adjustable to a position 50 tightly adjacent the face 28 located in the depressed groove 14 of the bed plate or base member. The last mentioned set of ways and the gibs together with their adjusting mechanism serve to prevent any movement of the column about 55 the bed plate. In other words, referring to Fig. 8, any tendency of the column to twist in the direction indicated by the arrows B is resisted. It is to be noted that I provide adjustments for the longitudinally located gibs on either side of the 60 bed plate thus permitting the shifting of the bed plate laterally if desired in order that proper adjustment may be had by the wedge shaped gibs 13 and their supporting members 32.

Referring now to Figs. 8 and 9, characters "A" 65 and "B" indicate arrows which show the several directions of movement which might be caused by the engagement of the tool 72 with the work. In Fig. 9, for example, the tool might be placed under a pressure which would tend to 70 lift it or lower it and, as previously described, the gibs 13 tend to prevent this movement between the column and the bed plate. Similarly, referring to Fig. 8, the tool might tend to move the column as indicated by the arrows "B" and, as 75 also previously set forth, the gibs 17 prevent this

movement. However, the reciprocating shaper bar 70 is mounted upon the apron 50 which must also transmit the several forces which have just been set forth.

As shown diagrammatically in Fig. 8 the column 80 30 has ways or guides 75, 76 and 77, the ways being engaged similarly to the engagement between the column and the bed plate. Hence, without entering into detail as regards this construction, suffice it to say, that this guiding connection between the saddle and the column is substantially identical with the guiding arrangement between the column and the bed plate. However, as shown in Fig. 9, the rear way is made considerably shorter than the other 85 two ways as this way or guide, together with its gib, tends to prevent movement of the reciprocating ram in a horizontal plane, as indicated by the arrows "B" in Fig. 8, and hence no reason obtains why it would be of any great length. In other 90 words the guiding means 75 and 76 prevent the turning of the ram 70 in the direction of the arrows "A", see Fig. 9, while the guiding means 75 and 77 prevent the movement of the ram in a 95 horizontal plane.

The weight relief consists of a carriage or 100 frame member 85 having a series of rollers 86 revolvably mounted therein, these rollers traversing the track 87 rigid with the bed plate 10. A series of cups 88, see Figs. 4 and 7, receive 105 springs 89 and bolts 60 are threaded through the base of the column and abut against plates 61 which in turn bear against the springs 89. Hence by tightening the bolts 60 the springs 89 are compressed to the desired degree thus tend to lift the 110 column member and all of its appurtenances off of the bed plate. Thus the friction between the base plate 31 of the column and the upper surfaces 11 of the bed plate 10 is lessened so that the column may be easily reciprocated back and 115 forth as desired. The springs are arranged in opposed relation so that their adjustment will govern the degree of bearing of either side of the column upon that particular side of the base, thus giving equal pressure at all points there- 120 between.

Having thus revealed this invention I claim as new and desire to secure the following combination and elements or equivalents thereof, by Letters Patent of the United States.

1. In a device of the class described, a member 125 having ways thereon, a second member slidably mounted upon said ways, gibs located on the second member in parallelism to the direction of movement of the two members, said first member having surfaces at right angles to the surface of contact between the two slidably mounted members, said surfaces adapted to be engaged by the said gibs, said first member having another set of surfaces parallel to the direction of 130 movement of the two members and at right angles to the previously mentioned surfaces on the first member, gibs on the second member adapted to slidably engage the last mentioned set of surfaces, said last mentioned surfaces with their 135 contacting gibs being spaced farther apart laterally than the other two gibs and their respective surfaces.

2. A device of the class set forth in claim 1 in which three of the four gibs have means for adjusting them with respect to their contacting surfaces.

3. In a metal planing machine, a base having a surface on which a column rests in part, a truck or carriage running on the base and supporting 150

the column in part, and springs arranged between the carriage and the column, whereby the weight of the column is partly carried on the carriage and partly carried on the said surface of the base, 5 said springs being located in pairs along the length of the carriage and on opposite sides of the carriage.

4. A combination of elements as set forth in claim 3 in which each spring has adjusting 10 means whereby it may be separately compressed as described.

5. In a traveling head shaper having a bed plate with ribs extending laterally therefrom, a column having a base portion slidably mounted 15 upon the bed plate, said base portion having overhanging parts extending underneath the ribs, gibs located between the bottom face of either rib and the overhanging parts, another gib located between the side face of one of the ribs and the 20 adjacent overhanging part whereby sidewise movement of the column in one direction is prevented, and means to prevent sidewise movement of the column in the opposite direction, both of the means for preventing sidewise movement of 25 the column with reference to the bed plate being adjustable whereby the column may be bodily shifted sidewise.

6. A device as set forth in claim 1 in which one of the gibs in each set is adjustable for the purpose described.

7. In a metal planing machine having a bed plate or base adapted to slidably receive a column thereon, the combination of ribs or shouldered portions extending from one of the slidably associated previously mentioned elements, overhanging portions on the other previously mentioned element, said shouldered portions having parallel ways engaged by the overhanging portions to prevent separation of the two elements, one of said shouldered portions having a way at right angles to the previously mentioned way formed thereon, means on the opposed overhanging portion engaging against the last mentioned way whereby lateral movement between the two elements in one direction is prevented and additional means between the two elements to prevent lateral movement in the opposite direction, 90 said additional means including a groove formed in one of the elements, a gib contacting against one side of the groove and means to fasten the gib to the other element.
